LOUIS GUSTAVE BRÉGUET AND PAUL ALBERT BRÉGUET, OF GENEVA, SWITZERLAND.

WIRE REDUCING.

Application filed December 5, 1921. Serial No. 520,110.

To all whom it may concern:

Be it known that we, LOUIS GUSTAVE BRÉGUET and PAUL ALBERT BRÉGUET, citizens of the Republic of Switzerland, residing at Geneva, Switzerland, have invented certain new and useful Improvements in Wire Reducing, of which the following is a specification.

The present invention relates to a wire-drawing machine of the kind wherein a rotating swaging mechanism is employed with a rotating head carrying radially movable dies.

The object of my invention is to provide means for facilitating the continuous reduction of wire from very large diameters to relatively very small diameters; and to that end, I provide a pair of rotating hammers having stepped working faces, the successive steps being connected by conical portions.

One form of machine embodying the present improvements is illustrated by way of example in the accompany drawing, wherein:

Figure 1 is a side elevation of said machine.

Fig. 2 is a detail view in vertical section, showing the wind-up reel and its driving means.

Fig. 3 is a face view of the hammering mechanism.

Fig. 4 is a sectional view taken axially of the hammers.

Fig. 5 is a plan view of Fig. 1.

In the form of machine represented, it will be assumed that the metal has already been converted into wire, the diameter of which is to be further reduced; and that this reduced wire, which is designated *i*, is wound up on a reel *j* located at one end of the frame *d* of the machine, and is designed to be unwound therefrom, fed through the machine and ultimately rewound, after having undergone the hammering treatment, upon a reel *s* at the other end of the frame.

The wind-up reel *s* is fixed to a horizontal shaft *s'*, suitably journaled and supported in the frame and driven from a main shaft *u* through the intermediary of helicoidal gearing *t*; said shaft carrying a stepped cone pulley *v* adapted to be connected with a source of power, to be driven thereby. The reel *s* has secured to it a pulley *s''* (Fig. 2) around which passes a belt *h*; and this

belt *h* also passes around and drives a pulley *g* mounted at the other end of the frame on a shaft *c* located adjacent the unwinding reel *j*. The shaft *c* has secured to it a frictional wheel *g'* which frictionally drives a feed roll *a* having a peripheral groove to receive therein the periphery of said wheel *g'* and, also, that of a lower feed roll *e*, between which rolls the wire *i* passes from reel *j*; the upper roll *a* being loosely mounted in a pair of arms *b* pivoted to shaft *c*, and being pressed against the roll *e* by a spring *f*, and against roll *g'* by springs *g''* as shown in Fig. 1.

On passing beyond the two coacting feed rolls *a* and *e*, the wire is led into and through the hammering mechanism which is disposed within a case *k* (Figs. 1 and 3) mounted upon the frame *d*. This mechanism comprises a pair of hammers *l* and *l'* arranged in suitable holders or carrier blocks *m* and *m'* which are mounted on one extremity of a hollow shaft *n* driven by a pulley *o* from a source of power. The blocks *m* and *m'* are provided at their outer ends with impact rollers *p* and *p'*, respectively, for coaction with an annular series of rollers *g* suitably mounted in the case *k*. The rollers *p* and *p'* are designed to rest loosely in their seats in the blocks *m* and *m'*, so that they will have a tendency to move outward therefrom, due to the action of centrifugal force, when shaft *n* is rotating. During their movement with the blocks, these rollers *p*, *p'* are caused to strike sharply against the successive roller *g*, the impact of the blows being transmitted to the blocks *m*, *m'* and thence to the hammers *l*, *l'*, which are thereby caused to act on the wire; it being understood that the latter is continuously fed forward by the rolls *a* and *e*.

The hammers *l*, *l'*, as previously stated, and as shown in Fig. 4, are stepped cross-section; the various cylindrical parts of different diameters of the opening between the hammers and forming the steps being connected by conical parts. This special construction enables the hammers to distribute along their entire length the effort necessary for hammering the material, and also acts to prevent the hammers from pushing back the material in opposition to its forward feed movement. As soon as the material advances, it is, at each blow of the hammer, at first seized at each angle formed by a

conical part and the preceding step, so that it is gripped at points before it can be forced back by the rest of the cone; the horizontal component which tends to press back the material thus losing its effect.

After having passed beyond the hammers, the hammered wire, indicated at i' , is led through a draw-plate r , the opening in which is disposed coaxial with the hollow shaft n .

We claim as our invention:—

1. In a wire-drawing machine for reducing very coarse wire at once to very fine wire, the combination of a pair of coacting hammers having a series of reducing rings formed into steps differing only slightly in diameter and connected by conical intermediate portions adapted to take a firm

grip on the wire; a wire-feeding mechanism; and operating means for the hammers.

2. In a wire-reducing machine, the combination of a pair of rotating coacting hammers between which the material to be treated is fed, said hammers having stepped working faces, and the successive steps thereof being connected by conical portions; a feeding mechanism for said material; operating means for the hammers; and a take-up device adapted to withdraw the reduced wire from the hammers.

In testimony whereof we affix our signatures.

LOUIS GUSTAVE BRÉGUET.
PAUL ALBERT BRÉGUET.
